United States Patent Office

Des. 179,295
Patented Nov. 27, 1956

179,295

TEXTILE FABRIC

William Edward Holt, Jr., Philadelphia, Pa., assignor to E. W. Twitchell, Inc., Philadelphia, Pa., a corporation of Pennsylvania

Application December 27, 1955, Serial No. 39,495

Term of patent 3½ years

(Cl. D92—1)

The single figure is a face view of a textile fabric showing my new design.

I claim:

The ornamental design for a textile fabric, substantially as shown.
